INVENTOR:

Andrea Gabriele Michele Pansa
by Chas. H. Luther

ATTORNEY:

UNITED STATES PATENT OFFICE.

ANDREA GABRIELE MICHELE PANSA, OF BRISTOL, RHODE ISLAND.

PISTOL-BAYONET.

1,231,058.

Specification of Letters Patent. Patented June 26, 1917.

Application filed May 3, 1917. Serial No. 166,171.

To all whom it may concern:

Be it known that I, ANDREA GABRIELE MICHELE PANSA, a native of Italy, residing at Bristol, in the county of Bristol and State 5 of Rhode Island, have invented a new and useful Improvement in Pistol-Bayonets, of which the following is a specification.

In the construction and use of a pistol or other small firearm having a bayonet, it is 10 desirable and necessary that the bayonet may be easily and quickly thrown into either its operative or inoperative positions and securely locked in either position. It is also desirable that when the bayonet is in 15 its operative position it should be in the best possible position for use and when not in use it should be held in the most out of the way position possible, without removing the same from the pistol, so that the bayonet 20 may be brought quickly into use when required. It should also be so placed as not to interfere in any way with the operation of firing the pistol, when the bayonet is in either position.

25 The object of my invention is to provide a pistol or other small fire-arm with a bayonet having all of the above desirable features and in which all undesirable features are entirely eliminated.

30 My invention consists in the peculiar and novel construction of a pistol bayonet adaptable for use on all kinds of small fire-arms, said pistol bayonet having details of construction, as will be more fully set forth 35 hereinafter and claimed.

Figure 1 is a side view of a pistol in the form of a revolver provided with my improved pistol bayonet and showing the bayonet in the open position for use in full 40 lines and the inoperative or closed position in broken lines.

Fig. 2 is a detail sectional view of the handle portion and showing the construction of the bayonet, and

45 Fig. 3 is an enlarged transverse sectional view taken on line 3, 3 of Fig. 1 through the pistol barrel and bayonet guard and showing the means of locking the bayonet in the closed position.

50 In the drawing 5 indicates a conventional form of a pistol and 6 my improved pistol bayonet. The pistol has the usual handle 7 and barrel 8. My improved pistol bayonet 6 consists of a hand member 9 shaped to conform to the hand and to go over the handle 7 of the pistol as shown. It is secured to the

handle of the pistol in any well known way or may form a part of the handle. A blade 10 forming the bayonet proper is constructed to have a pointed end 11, a notch 60 12 in the side adjacent the pointed end, a square butt end 13, a notch 14 in the outer edge adjacent the butt end and pivotally secured off center by a pin 15 in a slot 16 to the butt end of the hand member 9. The 65 slot 16 opens outward and at its inner end and has a flat bottom 17 abutting against the square butt end 13 of the blade 10, when the blade is in its open position, as shown in Fig. 2. A locking lever 18 held in its 70 normal position under spring tension, as shown, is pivotally secured by a pin 19 to and in the hand member 9 and has a beveled catch or locking end 20 which enters the notch 14 to lock the blade in its open position and an operating or thumb end 21 which extends out of the top portion of the hand member 9 in a convenient position for operation. A bifurcated guard 22 is secured to the underside of the muzzle end of the 75 barrel 8 into which the pointed end 11 of the blade is held, when closed by a catch lever 23, held in its normal position under spring tension, as shown, and having an inner beveled catch or locking end 24, which enters 80 the notch 12 in the blade 10 and holds the end of the blade in the guard, when the blade is in the closed position, and an outer releasing end 25 which extends through a slot in the side of the guard, as shown in 85 Fig. 3.

When it is desired or necessary to use the bayonet the end 25 of the catch 23 is pressed inward thereby releasing the bayonet which drops downward into its open position, as 90 shown in full lines in Fig. 1. The locking end 20 of the locking lever 18 now snaps into the notch 14 and with the bottom 17 of the slot 16 firmly holds the bayonet in the open position. With the position of the hand in 100 grasping the handle of the pistol for firing the bayonet is now in the best possible position for use. When not in use the bayonet is closed by pressing the thumb on the thumb end 21 of the locking lever 18 thereby 105 unlocking the bayonet by releasing the locking end 20 from the notch 14 in the bayonet, the end of which is then swung into the guard 22 and locked in the guard by the locking end 24 of the spring catch 23 snapping into the notch 12 in the bayonet.

By this construction the bayonet may be

quickly opened for use. It is in the best position for use when open and out of the way when closed and does not interfere with the operation of the pistol either in the open or closed position, also the bayonet is strongly and rigidly held in the open position when in use and it can be modified for use on any kind of a small fire-arm.

Having thus described my invention I claim as new:

1. In a pistol bayonet, a pistol having a barrel and a handle, a bayonet having a pointed end and a butt end, a guard on the pistol barrel, means for pivotally securing the butt end of the bayonet to the end of the pistol handle, means for locking the bayonet in the open position and means for detachably securing the pointed end of the bayonet in the guard, in the closed position.
2. In a pistol bayonet, a pistol having a barrel and a handle, a bayonet having a pointed end and a butt end, means for pivotally securing the butt end of the bayonet to the end of the pistol handle, a guard on the underside of the pistol barrel, means for locking the bayonet in the open position and means for detachably securing the pointed end of the bayonet in the guard, in the closed position.
3. In a pistol bayonet, a pistol having a barrel and a handle, a bayonet having a pointed end and a transverse butt end, means for pivotally securing the butt end of the bayonet to the end of the pistol handle, a guard on the underside of the barrel adjacent the muzzle of the barrel, means for locking the butt end of the bayonet in the open position and means for detachably securing the pointed end of the bayonet in the guard, in the closed position.
4. In a pistol bayonet, a pistol having a barrel and a handle approximately at right angles to the barrel, a bayonet having a pointed end and a squared off butt end, means for pivotally securing the butt end of the bayonet to the end of the pistol handle, a guard on the underside of the barrel adjacent the muzzle, means for unlocking or locking the butt end of the bayonet to the handle and means for detachably securing the pointed end of the bayonet in the guard.
5. In a pistol bayonet, a pistol having a barrel and a handle at approximately right angles to the barrel, a bayonet having a pointed end, a notch in the side adjacent the pointed end, a squared off butt end, a notch in its edge adjacent the butt end, means for pivotally securing the butt end of the bayonet to the end of the pistol han-

dle, a locking lever in the pistol handle, 60 adapted to engage with the notch in the edge of the bayonet and lock the bayonet in the open position, a guard on the underside of the barrel adjacent the muzzle and a spring catch in the guard adapted to engage 65 with the notch adjacent the point of the bayonet and detachably secure the pointed end of the bayonet in the guard.

6. The combination with a pistol having a barrel, and a handle approximately at 70 right angles to the barrel, of a pistol bayonet having a pointed end, a notch in the side adjacent the pointed end, a squared off butt end, a notch in its edge adjacent the butt end, means for pivotally securing the 75 butt end, off center, to the end of the pistol handle, a locking lever having a locking end adapted to engage with the notch in the edge of the bayonet and lock the bayonet in the open position, and a thumb end extending 80 outward from the top of the handle, a guard on the underside of the barrel adjacent the muzzle, and a spring catch in the guard having an outer projecting end, and an inner end adapted to engage with the 85 notch adjacent the point of the bayonet and detachably secure the pointed end of the bayonet in the guard.

7. The combination with a pistol having a handle 7 and a barrel 8, of a pistol bayonet 90 consisting of a hand member 9 shaped to conform to the hand and to go over the handle 7, a blade 10 forming the bayonet proper and having a pointed end 11, a notch 12 in the side adjacent the pointed end, a square 95 butt end 13, a notch 14 in the edge adjacent the butt end and pivotally secured off center by a pin 15 in a slot 16 to the butt end of the hand member 9, the slot 16 opening outward and at its inner end and having a flat bottom adapted to abut against the square butt end of the blade 10, a locking lever 18 held in its normal position under spring tension and pivotally secured by a pin 19 to and in the hand member 9 and having a beveled 100 locking end 20 and a thumb end 21 extending out of the handle, a bifurcated guard 22 on the underside of the barrel 8 adjacent the muzzle, a catch lever pivotally held in its normal position under spring tension and 110 having an inner beveled locking end 24, and an outer releasing end 25 which extends through a slot in the side of the guard, as described.

In testimony whereof, I have signed my 115 name to this specification.

ANDREA GABRIELE MICHELE PANSA.
